BRAKE

Walter H. Delahaye, Ottawa, Ontario, Canada,
assignor to Bendix Brake Company, South
Bend, Ind.

Application December 2, 1929. Serial No. 410,938

13 Claims. (Cl. 188—78)

The object of this invention is to provide a brake operated by either a cam, toggle or the like with a servo shoe of simple construction so coupled to the applying means that the servo force set up is applied through the minimum number of parts, thus simplifying the construction and providing one that is not liable to become deranged, so that the whole brake is such that it will retain its efficiency with the least possible attention. These objects are accomplished by the use of a servo shoe sliding on one of the main shoes similar to that set forth in, for example, applicant's co-pending Appln. Serial No. 410,941, filed December 2, 1929 and the specific details of which it is therefore not necessary to set forth herein.

The invention consists in the construction, combination and arrangement of parts hereinafter described and more particularly pointed out in the appended claims.

20 The drawing hereunto appended illustrates, by way of example, two embodiments of the improved structure,

Figure 1 being an elevation of the invention applied to a cam-operated brake, and

25 Figure 2 an elevation of the invention applied to a brake employing the well known type of toggle.

Referring to the drawing in which similar parts are designated by the same numerals in both figures, 1 represents the usual brake drum in which

30 a pair of shoes 2 and 3 are pivoted on the anchor

4. In the cam brake (Figure 1) these shoes have the customary cam engaging surfaces 5 and 6, adapted to be engaged by the cam 7, which is operated by the usual lever 8 adapted to be con-

35 nected to the brake rigging. The shoe 2 is of the usual type and has no additional features but the shoe 3 carries a servo shoe 9 as fully set forth in the above mentioned co-pending application.

Briefly, this shoe is adapted to slide on an offset

40 portion 10 of the shoe 3, which acts as a guide for the servo shoe instead of being furnished with a friction surface. Unlike the servo shoes disclosed in other application, in the construction herein disclosed, the servo shoe 9 which operates on the

45 guide 10 has an arcuate extension 11 which is provided with gear teeth which engage with the teeth of a segmental gear 12 fast on the shaft of the cam 7 or integral therewith.

Referring to Figure 2, it will be seen that the 50 servo may be similarly directly connected by inter-engaging teeth to the toggle applying means. This toggle applying means consists of the toggle 13 operated by the lever 14 through the arm 15 which is connected to the toggle 13 by means of 55 the link 16. The toothed extension 11 in this

case is made to mesh with the section of a gear that is fast to the pivot pin securing the toggle to the shoe 3, or which may be directly cut in the extremity of the arm of the toggle, the latter construction being shown in the drawing.

Various modifications may be made in the device and it is the intention of the applicant to claim all variations of construction in the scope of the appended claims.

I claim:

1. In a brake and in combination with a fixed support, a pair of shoes thereon, driver-operated applying means for the shoes and a servo shoe 70
slidable on one of the shoes, said servo shoe and said applying means having inter-engaging parts
adapted to transmit the servo action of the former to the latter means.

2. In a brake and in combination with a fixed support, a pair of shoes on said support, driver-operated means for expanding the free end of 75
said shoes, and a servo shoe carried by one of the shoes, said servo shoe and said expanding means
having inter-engaging parts to transmit the servo action of the servo shoe to the expanding
means.

3. In a brake and in combination with a fixed support, a pair of shoes thereon, expanding driver-operated means between the free ends of 80
said shoes, said expanding means including a
toothed member, and a servo shoe carried by one
of the shoes, said servo shoe having a toothed
extension engaging the first mentioned toothed
part to transmit a servo action from the servo
shoe to the applying means.

4. In a brake and in combination with a fixed support, a pair of shoes thereon, expanding driver-operated means between the free ends of 85
the said shoes, said expanding means including a
pivoted part having a toothed section, and a
servo shoe sliding on one of the first mentioned
shoes near the free end thereof, an extension on
the servo shoe having an arcuate toothed section
adapted to engage the first mentioned toothed
section to transmit a servo action from the servo
shoe to the said expanding means.

5. In a brake and in combination with a fixed support, a pair of shoes on said support, a pair of shoes pivoted on said support, a cam for expanding the shoes situated between the free ends 100
of said shoes, a shaft for operating the said cam,
means to operate the shaft, a servo shoe mounted
to slide on one of the shoes near the free end
thereof, and inter-engaging means on the servo
shoe and the shaft to transmit the servo action 105
110

of the servo shoe to the shaft and the cam carried thereby.

6. In a brake and in combination with a fixed support therefor, shoes movable thereon, expanding driver-operated means between two adjacent ends of the shoes, a servo shoe sliding on one of said ends, and inter-engaging portions on the expanding means and the servo shoe to transmit a servo action from the servo shoe to the expanding means.

7. In a brake and in combination with a fixed support therefor, a set of shoes mounted on said support adapted to be expanded into contact with a co-operating brake drum, means for causing the said expansion, a servo shoe carried adjacent the extremity of one of the shoes and sliding thereon adjacent the expanding means, a rotating part of the expanding means having a toothed portion and the said servo shoe having an extension overlying said toothed portion and having complementary teeth adapted to mesh therewith to transmit a servo action from the servo shoe to the expanding means.

8. In a brake and in combination with a fixed support therefor, a set of shoes mounted thereon, one of said shoes having an inwardly offset portion on which is slidably mounted a servo shoe adjacent an end thereof, expanding means for the said set of shoes between said end carrying the servo shoe and the next adjacent shoe, said expanding means including a shaft having a toothed portion carried thereby, an arcuate toothed extension on the said sliding servo shoe

overlying the said toothed portion and engaging the same to transmit a servo action caused by movement of the said servo shoe on the said offset portion to the shaft to augment the expanding effort applied thereto in the initial setting of the brake.

9. A brake comprising a friction element, a guide on the friction element, a servo shoe slideable on the guide and gear teeth on the shoe.

10. A brake comprising a friction element, a guide on the friction element, a servo shoe slideable on the guide, an extension on the servo shoe and gear teeth on the extension.

11. A brake comprising friction elements having separable ends, a servo shoe movable on one of the ends and means for spreading the separable ends including a gear segment for actuating the servo shoe.

12. A brake comprising friction elements having separable ends, a servo shoe movable on one of the separable ends, a rack on the servo shoe, a cam for spreading the separable ends and a gear segment associated with the cam and movable concomitantly therewith to actuate the servo shoe.

13. A brake comprising friction elements having separable ends, a servo shoe movable on one of the ends, a rack on the servo shoe, a toggle for spreading the separable ends of the friction element and a gear segment on the toggle engaging the rack on the servo shoe and means for applying force to the toggle.
